UNITED STATES PATENT OFFICE.

GEORGE DUNCANSON, JR., OF JERSEY CITY, NEW JERSEY.

PRINTER'S QUOIN.

Application filed August 4, 1921. Serial No. 489,799.

To all whom it may concern:

Be it known that I, GEORGE DUNCANSON, Jr., a citizen of the United States, and a resident of Jersey City, in the county of 5 Hudson and State of New Jersey, have invented a new and Improved Printer's Quoin, of which the following is a full, clear, and exact description.

The present invention relates to new and 10 useful improvements in printer's quoins and the same is an improvement on the device disclosed in United States Letters Patent No. 1,375,495, granted to me April 19, 1921.

It is one of the objects of the invention 15 to provide a printer's quoin which after the same is set it may be locked to prevent accidental displacement of the parts when in use.

It is a further object of the invention to 20 provide a printer's quoin in which the two wedge blocks which go to make up the quoin will be freely movable with respect to one another.

It is a still further object of the invention 25 to provide a locking means for the wedge blocks of a printer's quoin in which the locking means serves also as means for retaining the wedge blocks against accidental displacement when they are not in use.

30 With the above and other objects in view, reference is had to the accompanying drawings, in which—

Figure 1 is a view in side elevation of a 35 printer's quoin constructed in accordance with the present invention;

Fig. 2 is an end view of one of the wedge blocks of the quoin;

Fig. 3 is a vertical sectional view taken on the line 3—3 of Fig. 1;

40 Fig. 4 is a detail side elevational view of one of the blocks which go to make up the quoin.

Referring more particularly to the drawings, the quoin comprises two triangular-shaped blocks 5, with their angular faces 45 placed together in such a manner that relative movement of the blocks longitudinally produces an increase in the transverse dimension of the quoin as is the common practice in devices of this character.

Each of the blocks is provided with a plurality of rack teeth 6 for the reception of a key by means of which the two blocks 5 are moved longitudinally as above de-

scribed. Each block 5 is provided with a 55 central web 7 and each of said central webs 7 is provided with an offset vertical wall 8. As more clearly shown in Fig. 4, each of these offset vertical walls 8 is provided with an elongated slot 9 and passing through 60 each of said walls adjacent one end of its respective slot is a screw-threaded opening 10. Each of these screw-threaded openings 10 is adapted to receive a bolt 11, as more clearly shown in Fig. 3. By this construction it is apparent that each of the blocks 5 carries a screw-threaded member, and it will be noted that the screw-threaded member of each block passes through and has movement in the elongated slot of the other 70 block in order to provide for the relative longitudinal movement of the two blocks 5. The enlarged end of each of the blocks 5 is provided with a slot 12 or the like in which the offset portion of the opposite 75 block slides, it being noted that the slot 12 is offset with respect to the transverse center of each block.

Assuming now that the quoin is desired 80 for use, it is placed in position between the type matter and the chase and the two blocks are moved relatively one to the other by the fingers of the operator until they frictionally engage both the type matter and the chase. After this has been accomplished, the key is inserted into engagement with the teeth 6 and the members are moved by the key until they are tightened in position as is the common practice. After the members have been so positioned and tightened by 85 means of the key, the screw-threaded members 11 are tightened until they clamp between their headed portions and the offset portion by which they are carried, the offset member of the opposite block with which 90 they have sliding movement, thus locking the two wedge blocks of the quoin against longitudinal movement while they are in position in the chase.

By providing each wedge block of the 100 quoin with a screw-threaded fastening 11, it will be seen that in order to gain the desired results, the heads of the screw-threaded fastenings are oppositely disposed, thus making it immaterial from an operative point of view, in which position the quoin is placed within the chase, since in either position the head of one of the screw fastenings is avail- 105

able in order that it may be turned up to lock the blocks against longitudinal movement.

I claim:

- 5 1. A printer's quoin comprising a pair of wedge blocks, a slotted web carried by each of said blocks, said slotted webs being adapted to lie parallel one to the other, and means carried by each of said blocks and projecting through the slot of the slotted web of the opposite block to secure the blocks against relative movement.
- 10 2. A printer's quoin comprising two wedge blocks movable longitudinally with respect to one another, and screw threaded means carried by each of said blocks and adapted for interengagement with the other block to positively lock said blocks against movement in either direction, as and for the purpose set forth.
- 15 3. A printer's quoin comprising a pair of blocks, each of which is provided with an offset web, a screw having threaded engagement with the web of each block, and in sliding engagement with a portion of the other block, whereby the screw when tightened prevents relative movement of the blocks.
- 20 4. A printer's quoin comprising a pair of wedge-shaped blocks movable longitudinally with respect to one another, an offset slotted

web formed integral with each of said blocks, a screw having threaded engagement with a portion of the web in each block, each of said screws having sliding engagement with the slotted web of the opposite block from that by which the screw is carried, said screws serving to retain the blocks together to form a unitary structure and also serving to lock the blocks against longitudinal movement, as and for the purpose set forth.

5. A printer's quoin comprising a pair of blocks, and means carried by each of said blocks, each of said means having threaded engagement with the block by which it is carried and having sliding movement with the other block as and for the purpose set forth.

6. A printer's quoin comprising a pair of sliding wedge-shaped blocks each of which has a slotted flange, and means carried by each block and operable through the slot of the flange of the other block to secure the blocks together as a unit.

7. A printer's quoin comprising a pair of blocks each of which is provided with a slotted flange, and means carried by the flange of each of said blocks, and operating through the slot in the flange of the opposed block, said means serving to bind the flanges of the blocks together to prevent relative movement of the blocks.

GEORGE DUNCANSON, JR.
